(57) **CLAIM**

The ornamental design for a bath tray, as shown and described.

DESCRIPTION

FIG. 1 is a perspective view taken from the top, front, and left side of a bath tray showing my new design;

FIG. 2 is a right side elevation view thereof, the opposite side being a mirror image thereof;

FIG. 3 is a bottom plan view thereof;

FIG. 4 is a top plan view thereof;

FIG. 5 is a front elevation view thereof; and,

FIG. 6 is a rear elevation view thereof.

The broken lines in the drawing views are included for illustrating portions of the bath tray that do not form part of the claimed design.

1 Claim, 6 Drawing Sheets
